UNITED STATES PATENT OFFICE.

ALEX BERNSTEIN, OF CHICAGO, ILLINOIS.

SHIRT-BAND TAB.

1,175,403.

Specification of Letters Patent. Patented Mar. 14, 1916.

Application filed March 6, 1915. Serial No. 12,527.

To all whom it may concern:

Be it known that I, ALEX BERNSTEIN, a citizen of the United States, and a resident of the city of Chicago, in the county of Cook and State of Illinois, have invented 5 certain new and useful Improvements in Shirt-Band Tabs; and I do hereby declare that the following is a full, clear, and exact description of the same, reference being had 10 to the accompanying drawings, and to the numerals of reference marked thereon, which form a part of this specification.

This invention relates to the construction 15 of tabs for use on shirts having no neck or collar bands, so that a collar may be attached to the shirt by means of said tabs and without the inconvenience arising such as is sometimes occasioned by collar bands when the collars are not of the proper relative size to be correctly fastened around the band.

It is an object therefore of this invention 20 to construct an improved device for connection upon the neck portions of shirts to provide a means for attaching a collar thereto.

It is furthermore an important object of 25 this invention to construct detachable tabs for attachment at the front and back of a shirt neck to provide a means of connection thereto of a collar, thus obviating the necessity of a shirt collar band, and permitting collars of different size than the shirt within certain ranges, to be conveniently 30 worn therewith.

It is finally an object of this invention to 35 provide an improved construction for attaching collars to shirts obviating the necessity of the ordinary stiff starched collar shirt bands and the disadvantages which result 40 from the use thereof, of which the tearing of the shirt fabric from the band is the most general objection.

The invention (in a preferred form) is 45 illustrated in the drawings and hereinafter more fully described.

In the drawings, Figure 1 is a fragmentary perspective view of the neck of a shirt equipped with attaching tabs embodying the principles of my invention. Fig. 2 50 is a fragmentary top view of the tab attached at the back of the shirt neck. Fig. 3 is a similar view of the tab attached at the front of the shirt neck. Fig. 4 is a front elevation of the tab used at the front of the shirt neck. Fig. 5 is a detail section taken

on line 5—5 of Fig. 1. Fig. 6 is a detail section taken on line 6—6 of Fig. 1. Fig. 7 is a view similar to Fig. 1, illustrating a modified form of tab used with the shirt. 60 Fig. 8 is an interior elevation of the tab used at the back of the neck. Fig. 9 is a top edge view thereof. Fig. 10 is a detail section taken on line 10—10 of Fig. 7.

As shown in the drawings, the body of a 65 shirt is denoted by the reference numeral 1, and the neck thereof by the reference numeral 2, the neck and body of the shirt opening at the front in the usual manner. The neck of the shirt may preferably consist of merely a soft finished edge of the 70 fabric in place of the customary stiff upright collar band usually provided. Attaching tabs are mounted on the neck at the front and rear thereof to afford means 75 of connection for a collar to the shirt, the tab at the back of the neck being denoted as a whole by the reference numeral 3, and the tab at the front of the neck by the reference numeral 4, said tabs being preferably constructed of a relatively stiff material, for instance celluloid or the like.

Rigidly secured upon the tab 3, are a pair 80 of attaching buttons 5, which, as clearly shown in Fig. 2, are adapted to engage 85 through buttonholes provided in the neck 2, of the shirt, to hold the tab attached thereto, and also securely fastened in said tab 3, is a back collar button 6, to receive 90 a collar fastened thereon. The front tab 4, 95 is almost exactly the same in construction, the only difference being that attaching buttons 7, are provided on one side of the tab, and a front collar button 8, is rigidly secured on the opposite side thereof, as clearly 100 shown in Fig. 3. In order to attach the tab 4, in place, the neck 2, is provided with pockets 9, on each side thereof provided with suitable buttonholes to receive the buttons 7, therethrough, so that the tab 4, when 105 attached position, lies between the pocket members, and the front fabric portion of the neck 2.

In the modification of my invention illustrated in Figs. 7 to 10 inclusive, I have 110 illustrated attaching tabs for connection at the front and back of the shirt neck which may preferably be made of fabric and thus conveniently laundered. The latter tabs are denoted respectively by the reference numerals 10 and 11, and the back tab 10, is provided with buttons 12, stitched thereto

for insertion through buttonholes provided in the neck of the shirt, which is designated by the reference numeral 13. Said tab 10, is provided with a buttonhole 14, through 5 which a back collar button may be inserted for attachment of a collar thereto. The front tab 11, is provided with small buttonholes at each end thereof to receive attaching buttons 15, therethrough, as clearly 10 shown in Fig. 10, the buttons 15, being stitched on the interior of the neck 13, or the shirt. Said front tab 11, is also provided with a central buttonhole 16, similar 15 to the buttonhole 14, of the back tab, to receive inserted therethrough a front collar button for attachment of the collar to the shirt.

The operation of my invention is thought to be obvious from the description. It is 20 apparent, however, that by the use of a detachable connecting means for the collar to the shirt, the stiff starched collar band forming a part of the shirt itself may be dispensed with, and thus a number of 25 disadvantages overcome. The tabs 3 and 4, shown in Figs. 1 to 6 inclusive, entirely obviate the use of separate collar buttons, so that the inconvenience occasioned by the loss of a collar button is thereby avoided. 30 The fabric attaching tabs illustrated in

Figs. 7 to 10 inclusive afford a convenient means of attachment of a collar to a shirt and of course may be longer, and if desired may be made a part of the shirt and permanently stitched thereto.

I am aware that various details of construction may be varied through a wide range without departing from the principles of this invention, and I therefore do not purpose limiting the patent granted 40 otherwise than necessitated by the prior art.

I claim as my invention:

1. The combination with a neckbandless shirt, of upstanding tabs detachably connected to the neck portion thereof, and 45 means on said tabs for connecting a collar thereto.

2. The combination with a neckbandless shirt, of means for connecting a collar to the neck portion thereof, comprising upstanding tabs detachably secured at the front and rear of said neck portion.

In testimony whereof I have hereunto subscribed my name in the presence of two subscribing witnesses.

ALEX BERNSTEIN.
